CLAIM

The ornamental design for an oral care apparatus, as shown and described.

DESCRIPTION

FIG. 1 is a front right perspective view of an oral care apparatus according to our new design;

FIG. 2 is a front view thereof;

FIG. 3 is a rear view thereof;

FIG. 4 is a right side view thereof;

FIG. 5 is a left side view thereof;

FIG. 6 is an enlarged top view thereof; and,

FIG. 7 is an enlarged bottom view thereof.

The broken lines showing portions of the oral care apparatus form no part of the claimed design. The dot-dash broken lines define the bounds of the claimed design and form no part thereof.
